CLAIM

The ornamental design for a portion of a miter saw, as shown and described.

DESCRIPTION

FIG. 1 is a front perspective exploded view of a portion of a saw.

FIG. 2 is a side view of the portion of a saw of FIG. 1.

FIG. 3 is another side view of the portion of a saw of FIG. 1.

FIG. 4 is a top view of the portion of a saw of FIG. 1; and, FIG. 5 is a front view of the portion of a saw of FIG. 1.

The present application is directed to the shape and contour of the design illustrated in the drawings. Other features of the drawings, specifically, portion of the table portion of the miter saw, are not considered part of the design sought to be patented, and have accordingly been shown in broken lines.
